US00D618702S

(12) **United States Design Patent**
Lee

(10) **Patent No.:** US D618,702 S
(45) **Date of Patent:** ** Jun. 29, 2010

(54) **VIDEO DISPLAY IMAGE FOR MOBILE PHONE**

(75) Inventor: **Joo-Hyun Lee**, Seoul (KR)

(73) Assignee: **Samsung Electronics Co., Ltd.**, Suwon-Si (KR)

(**) Term: **14 Years**

(21) Appl. No.: **29/336,170**

(22) Filed: **Apr. 29, 2009**

(30) **Foreign Application Priority Data**

Jan. 16, 2009 (KR) 30-2009-0001902

(51) **LOC (9) Cl.** 32-00

(52) **U.S. Cl.** **D14/486**

(58) **Field of Classification Search** D14/485-495; 715/700-867

See application file for complete search history.
